UNITED STATES PATENT OFFICE.

JOHN L. JENKINS, OF PORT CHESTER, NEW YORK.

UNIVERSAL TOOL TURRET.

Application filed September 30, 1920. Serial No. 413,837.

To all whom it may concern:

Be it known that I, JOHN L. JENKINS, a citizen of the United States, residing in Port Chester, in the county of Westchester and State of New York, have invented certain new and useful Improvements in Universal Tool Turrets, of which the following is a specification.

This invention relates to turrets or other tool holders for lathes and machine tools generally.

The device consists primarily in a two-part turret element, preferably made in upper and lower halves for convenience in machining the bores or seats for tool shanks. The device also consists in improved means for attaching said turret to the transverse slide of a lathe. Said last means comprises a separable base member having means thereon for engaging the T-headed slot or other cross-slide designed to make it universally engageable with any shape or form of slot such as is customarily met with upon the above noted slides. In ordinary shop practice different slots have different dimensions, and the various tool posts usually carried thereby also have various dimensions and structure, and consequently the anchoring means for the individual tool post must correspond to the peculiarities in design and the common practice of the manufacturers of the individual machines.

Ordinarily this particular problem of mounting turret adaptors of this type is met by providing an entirely different new cross head to be substituted for the customary tool cross head and holder supplied by the makers; and this involves a large expense, inasmuch as the manufacturer of such turret must keep constantly in touch with all the many various forms, dimensions and types of slides on the different lathes ordinarily in use in machine shop practice. The new device herein described is quickly adjustable to any one of these various designs.

Another advantage in my new type of turret, in addition to the universal turret and lathe attaching means just noted, is the base member having two outstanding features of construction. One of these comprises an adjusting means whereby the turret may be raised and lowered, thereby adapting it for vertical adjustment in order

to align the tool with the axis of the lathe live-spindle, the transverse horizontal adjustment of the turret devices being attained by operating the regular cross slide attachment adjustment as in the usual way now used with any lathe. It will therefore be seen that with the transverse and vertical adjustment the turret holder is easily and quickly adjusted to the axis of the live-spindle, whereby truly concentric work may be performed.

The second outstanding important feature is the provision of means upon said base element in the form of a tapered or chamfered upper edge which in cooperation with a seat in the turret provides for an extremely rigid mounting heretofore very difficult to obtain in such constructions.

Some of the main advantages in the use of my new turret are the ease with which an ordinary lathe may be turned into a turret lathe, thereby permitting, during the manufacture of certain kinds of articles, preferably of metal, the performing of a large number of sequential and varying turning, facing and boring operations upon such article while carried in the chuck on the live-spindle of the lathe. An obvious advantage afforded by the present form of construction is the elimination of a substituted slide for the slide already on the lathe, owing to its universal lathe attaching means and its two-way adjustability of turret centers, thus providing practically universal tool for any and all lathes within a given range of capacity which may be readily adapted and adjusted for such varying types of lathes where they are within the limit of proportions and capacities of the turret or vice-versa.

These and other objects and advantages will appear as the description proceeds; and while herein minute details of the invention are disclosed, the invention is not limited to these since many and various changes may be made without departing from the scope of the invention as claimed.

In the accompanying drawings, showing by way of example one of many possible embodiments of the invention,

Figure 1 is a plan of the new turret;

Fig. 2 is a side elevation partly in section;

Fig. 2^a is a fragmental sectional view showing the turret attached to the slot of the slide;

Fig. 3 is a bottom view of the turret base; 5 and

Figs. 4 and 5 are central vertical sectional views showing the turret in lowered and raised adjusted positions respectively.

My improved tool turret is adapted for 10 use with variously dimensioned transverse lathe slides, and particularly lathe slides having base members, such as 10, provided with slots, such as the slot 11 of inverted T-shaped cross-section forming undercut side flanges 12, shown in Fig. 2^a.

The turret is mounted on a peripherally threaded swivel post or base 15 (Fig. 4) for disposition over the base 10 of the slide and is rotatable horizontally. The swivel post or base 15 is beveled at its upper edge 16 to 20 form a low truncated cone. An interiorly threaded adjusting ring 18 is arranged for engaging the exterior thread on said swivel post or base to raise the swivel post or base 25 and the turret to different heights above the slide (Fig. 5); or permit the swivel post or base to seat on said ring, by screwing movement of the swivel post or base in said ring, the swivel post or base being held in desired 30 position relative to said ring by a set screw 19.

A clamp-plate 20 spaced from said base and disposed longitudinally of said T-slot under both of said side flanges may be adjusted as to height by clamping screws 21 35 passing through base 15 and into said clamp-plate for clamping said base on the slide, whatever height the base is held by the ring 18. A positioned tongue element 24 (Fig. 40 3) is disposed longitudinally of said T-slot between said flanges 12 against one of the flanges and is adapted to be fixed by screws 25 in several positions of adjustment on the under face of said base, as shown by the 45 dotted lines. An adjustable tongue element 26 is disposed in said T-slot between said flanges against the other flange 12 and is adjustably spaced from fixed element and provided with transverse slots 27 in which 50 engage clamping screws 28 passing through said transverse slots into the swivel base for clamping the adjustable element in adjusted position. By adjusting these tongue-elements 55 whatever may be the distances between the flanges 12.

A stud 30 (Fig. 4) received in a central bore 31 in the base 15 and provided with a threaded upper end receives a turret 32 60 formed of a top head 33 and a bottom head 34 secured together with suitable screws 35 (Fig. 1) to form contacting faces or a plane of parting 36. This head is provided with a central bore 37 received on said stud and 65 with radial square tool seats 38 (Fig. 2) just

below said plane and with radial round tool seats 39 intersecting but principally below said plane.

The lower face of said bottom head is provided with a shallow tapering recess 40 70 (Fig. 4) having inclined side walls 41 snugly received on said bevelled edges 16 of the base; and a locking handle 42 (Fig. 2) having a tapped bore 43 (Fig. 4) received on said stud 30 is adapted for locking said turret 75 head on the base with a wedging action at said edge 16 and wall 41.

A lock-pin 44 (Fig. 2) in each lock pin bore 45 has a clamping nut 46 at the upper end and is provided with a cut away portion 47 approximately coincident with the wall of the round tool seat 39. Set screws 48 are provided for holding square tools in the square tool seats. 80

An index pin 50 in the vertical index bore 51 is provided with an upper-end manipulating head 52 and at its lower end with an enlarged locking head 53 adapted to engage in any one of eight or more equally spaced index openings 54 in the base 15. A spring 55 on the index pin compressed between said enlarged head 53 and a shoulder 56 at the upper end of the bore yieldably holds the index pin in place. The top and bottom heads of the turret are each turned up separately, and the square tool seats are then cut in the bottom head. Provision is then made for the screws 35, and the remaining seats and boxes are drilled after the heads are secured together. 95

The operation of the device will be readily apparent from the foregoing. The turret portion is removed by releasing the handle 42 and by means of the screws 25 and 28 (Fig. 3), the tongue elements 24 and 26 are adjusted to fit between the flanges 12 (Fig. 2^a) of the slide. The clamp plate 20 is then placed under the flanges 12 and held by means of the screws 21. The turret portion is then replaced and turned on the base 15 100 until the desired position of rotation is reached and the index pin allowed to engage in the desired opening 54. The required tool being locked in its seat, the turret and swivel post are then rotated in the ring 18 105 until the tool assumes the correct height relative to the axis of rotation of the work, the swivel post being locked in this position by the set screw 19. The turret is then clamped firmly in position by means of the handle 42. 110

After each operation, the handle 42 is loosened and the turret turned to bring the succeeding tool in place.

Other modes of operation will readily suggest themselves. 125

Having thus described my invention, I claim:

1. In a universal tool turret, the combination, with a lathe slide, of a circular base threaded on its periphery; a turret rotatable 130

- horizontally on said base provided with tool carriers; an interiorly threaded ring engaging said base for raising or lowering the base and turret for alinement of said tool-carriers with the axis of the lathe live spindle; and means for removably attaching said base to the slide.
2. In a universal tool turret, the combination, with a lathe slide, of a circular base 10 threaded on its periphery; a turret rotatable horizontally on said base provided with tool carriers; an interiorly threaded ring engaging said base for raising or lowering the base and turret for alinement of said tool-carriers with the axis of the lathe live spindle; and means for removably attaching said base to the slide.
3. In a universal tool turret, the combination, with a lathe slide, of a circular base 20 threaded on its periphery and having a truncated cone-shaped upper portion; a turret rotatable horizontally on said base provided with tool carriers and having a recessed lower portion for conformably engaging said truncated cone-shaped upper portion; means for rotatably supporting the turret on said base, the turret being separable from the base; an interiorly threaded ring engaging said base for raising or lowering the base and turret for alinement of said tool-carriers with the axis of the lathe live spindle; and means for removably attaching said base to the slide.
4. In a universal tool turret, the combination, with a lathe slide, of a circular base 30 threaded on its periphery and having a truncated cone-shaped upper portion; a turret rotatable horizontally on said base provided with tool-carriers and having a recessed lower portion for conformably engaging said truncated cone-shaped upper portion; means for rotatably supporting the turret on said base, the turret being separable from the base; means for releasably locking said base and turret in conforming engagement of said lower and upper portions; an interiorly threaded ring engaging said base for raising or lowering the base and turret 40 for alinement of said tool-carriers with the axis of the lathe live spindle; means for retaining the base in raised or lowered position; and means for removably attaching said base to the slide.
5. In a universal turret tool having a supporting base, the combination, with a lathe slide provided with an attachment slot comprised of a stem portion having side walls and a portion transverse to the stem portion, of the supporting base of the turret tool; and means for attaching said base to the slide slot; said means comprising clamping members carried by said base engageable with the transverse portion of the slide slot, and co-operating members carried by said base engageable with the side walls of the stem of the slide slot; one of said co-operating members being fixedly positionable on the base, and the other of said members being adjustably movable on the base for regulating the space between said members for engagement of the members with the side walls of the slide slot.
6. In a universal turret tool having a supporting base, the combination, with a lathe 75 slide provided with an attachment slot comprised of a stem portion having side walls and a portion transverse to the stem portion, of the supporting base of the turret tool; and means for attaching said base to the slide slot; said means comprising clamping members operatively connected to said base and engageable with the transverse portion of the slide slot, and co-operating members operatively connected to said base and engageable with the side walls of the stem of the slide slot; said co-operating members being movable for spacing them apart to meet the width of the space between said side walls for engagement of said members 80 with said side walls.
7. In a universal turret tool having a supporting base, the combination, with a lathe slide provided with an attachment slot comprised of a stem portion having side walls 95 and a portion transverse to the stem portion, of the supporting base of the turret tool; and means for attaching the base to the slide slot; said means comprising clamping members carried by said base engageable with the transverse portion of the slide slot, and co-operating members carried by the base engageable with the side walls of the stem of the slide slot; one of said co-operating members being fixedly positionable on the base, 100 and the other of said members being movable on the base and adjustable by slot and pin means for regulating the space between said members for spacing them apart for engagement with the side walls of the stem 105 of the slide slot.
8. In a universal turret tool having a supporting base, the combination, with a lathe slide provided with an attachment slot comprised of a stem portion and a portion transverse to the stem portion, of the supporting base of the turret tool; a turret on said base provided with tool carriers; and means for clamping said base to the slide slot; said means comprising clamping members operatively connected to said base engageable with the transverse portion of the slide slot, and co-operating members operatively connected to said base engageable with the side walls of the stem of the slide slot; and said 115 turret being separable from said base for permitting adjustment of said clamping means to the slide slot.
9. In a universal turret tool having a supporting base, the combination, with a 120
- 125
- 130

- lathe slide provided with an attachment slot comprised of a stem portion and a portion transverse to the stem portion, of the supporting base of the turret tool; a turret on 5 said base provided with tool carriers; and means for clamping said base to the slide slot; said means comprising clamping members operatively connected to said base and engageable with the transverse portion of 10 the slide slot, and co-operating members operatively connected to said base engageable with the side walls of the stem of the slide slot; said co-operating members being movable for spacing them apart to meet the 15 width of the space between said side walls for engagement of said members with said side walls; and said turret being separable from said base for permitting adjustment of said clamping means to the slide slot.
- 20 10. In a universal turret tool having a supporting base, the combination, with a lathe slide provided with an attachment slot of inverted T-shape, of the supporting base of the turret tool; a turret on said base provided with tool carriers; and means for clamping said base to the slide slot; said means comprising clamping members carried by said base engageable with the trans- 25 verse portion of the slide slot, and co-oper- 30 ating members carried by said base engageable with the side walls of the stem of the slide slot; one of said members being
- fixedly positionable on the base, and the other of said members being movable on the base and adjustable by slot and pin 35 means for regulating the space between said members for spacing them apart for engagement with the side walls of the stem of the slide slot.
11. In combination, a slide having a slot 40 forming side flanges; a base; a tongue on the base between the flanges and laterally adjustable in width; a clamping plate adjustably secured to said base to clamp under the flanges and adjustable relatively to said 45 tongue; and a tool holder on said base.
12. In combination, a slide having a slot forming side flanges; a base; a clamping plate secured to said base to clamp under the flanges; a tongue on the base between the 50 flanges and adjustable in width independently of said plate; and a tool holder on said base.
13. In combination, a slide having a slot forming side flanges; a base; a one piece 55 clamping plate secured to said base to clamp under said flanges; a tongue adjustable in width secured to the lower face of the base between said flanges; and a tool holder on said base.

JOHN L. JENKINS.
